CONVEYER MECHANISM FOR WRAPPING MACHINES AND THE LIKE

John W. Smith, Battle Creek, Mich., assignor to
Battle Creek Bread Wrapping Machine Company, Battle Creek, Mich.

Application May 2, 1947, Serial No. 745,370

6 Claims. (Cl. 53—122)

1

This invention relates to improvements in conveyor mechanisms for wrapping machines and the like.

The principal objects of this invention are:

First, to provide mechanism for lifting a quantity of articles to be wrapped on a bottom supporting panel vertically from a continuously advancing conveyor upwardly through a wrapper feed table to an upper wrapper and transfer station where the folding and wrapping of the package may be completed.

Second, to provide elevator mechanism for transferring a quantity of articles from or to a continuously advancing conveyor in which the elevator will move both vertically and horizontally in timed relationship with the conveyor so that the conveyor need not be stopped during the transfer operation.

Third, to provide novel operating cams and linkage for the elevator of a wrapping machine by means of which the elevator may be actuated to move upwardly between the sides of a pocket of a loading conveyor and downwardly through the same pocket during the time in which the pocket is passing the elevator station.

Fourth, to provide novel wrapping mechanism for packaging various articles in which stacks of the articles on bottom panels may be continuously advanced to a wrapping station without intermittent stopping and starting of the packages which slows down the machine and is liable to dislodge the stacks.

Fifth, to provide wrapping mechanism by means of which a number of articles may be automatically packaged and wrapped on a flat supporting panel eliminating the need for more expensive side walled containers.

Other objects and advantages pertaining to the details and economies of the invention will be apparent from the following description and claims.

The drawings, of which there are three sheets, illustrate a preferred form of my elevator mechanism as applied to a machine for wrapping several cookies in a package.

Fig. 1 is a fragmentary vertical longitudinally cross sectional view through the wrapping machine taken along the broken line 1—1 in Fig. 3 and showing the elevator in lowered position.

Fig. 2 is an enlarged fragmentary elevational view partially broken away in cross section of the operating cams and linkage for actuating my elevator and illustrating the successive positions of the elevator in dotted lines.

Fig. 3 is a fragmentary plan view, partially

5 broken away, of my elevator mechanism with the wrapper feed and folding mechanism removed from the top thereof to clearly illustrate the elevator and its relationship to the conveyor for advancing the food packages.

In the wrapping of food articles, particularly baked goods, it has been the practice to provide a loading conveyor having laterally and longitudinally adjustable flights of loading pockets in which are placed bottom panels of light cardboard for supporting the baked goods and upon which the baked goods are placed either automatically or by hand as they come from the baking ovens. The baked goods and bottom panels are then advanced by the loading conveyor to an elevating station where mechanism is provided for lifting the bottom panel with the baked goods thereon vertically upward through an opening in a wrapper feed table so that the package is pressed upwardly underneath a piece 10 of wrapping paper. The package and wrapper are pressed upwardly through an opening in a wrapping table in such a fashion that the wrapper is folded downwardly over the sides of the package and transfer mechanism is provided 15 above the wrapping table for folding the ends of the wrapper about the package and transferring the package off of the elevator in such a fashion as to fold the bottom of the wrapper across the bottom of the package. In previous machines it 20 has been necessary to operate the loading conveyor intermittently so that the pockets will be stopped over the elevator position during the time in which the elevator is lifting each package and returning to its lowered position. This practice has been satisfactory when wrapping such articles as bread and cakes of a solid nature but has proved unsatisfactory when wrapping a series of cookies in which the cookies are loosely 25 stacked on the bottom panel because the intermittent starting and stopping of the loading conveyor results in the stacks of cookies being jiggled and toppled from the bottom panel. It has therefore been necessary to use more expensive side walled boxes for packaging cookies. By means 30 of my elevator mechanism the loading conveyor may be operated smoothly and continuously eliminating the tendency for the stacks of cookies to be toppled and dislodged. This permits the use of inexpensive flat bottom panels to support the cookies on the loading conveyor.

As illustrated in the drawings, my wrapping machine is provided with a pair of suitable side frame members 1 which support across their top 35 the wrapper feed table 2 having the aperture 3

55

formed therein through which the package of cookies is to be raised. The wrapping table is indicated at 4 vertically above the wrapper feed table and is provided with an elevator opening 5 directly above the opening in the wrapper feed table. Folding and transferring mechanism is conventionally illustrated by the dotted lines at 6 for folding the wrapper around the package and transferring the package from the elevator.

The ends of the side frame members 1 carry a motor support 7 on which the driving motor 8 is mounted. The motor is belt connected to a pulley on the driving shaft 9 journaled in the side frame members 1 and the shaft 9 is provided with a pinion 10 (see Fig. 3) for driving a gear 11 on the jack shaft 12. The jack shaft 12 is provided with a bevel gear 13 driving a mating bevel gear on the lay shaft 14 journaled in brackets on the forward side frame member. The lay shaft 14 is provided with a second bevel gear 15 driving a mating bevel gear on the driven shaft 16 which is also journaled in the side frame members and which extends beyond each side of the side frame members. The driven shaft 16 is provided with a sprocket and chain drive 17 to the conveyor shaft 18 from which the loading conveyor chains 19 are operated. The loading conveyor is of a design familiar to the wrapping machine art being provided with inner and outer chains carrying forward pocket members 20 and rear pocket members 21 forming flights of loading pockets.

Journalized in the side frame members 1 to the left of the driven shaft 16 as viewed in Figs. 1 and 3 is a rock shaft 22 having a bifurcated crank arm 23 secured thereto underneath the center of the loading conveyor. The crank arm 23 is pivotally connected to an upper elevator arm 24 and the rear end of the rock shaft 22 is provided with a second crank arm 25 (see Figs. 2 and 3) carrying a cam roller 26. The cam roller 26 is engaged in and actuated by the cam groove 27 formed on the inside of a cam wheel 28 secured to the rear end of the driven shaft 16. (See Figs. 2 and 3.)

It will thus be seen that as the driven shaft 16 and cam wheel 28 are rotated by the lay shaft, the loading conveyor will be advanced and the crank arm 25 will actuate the rock shaft 22 and crank arm 23 to oscillate the elevator arm 24 according to the contour of the cam groove 27.

Positioned below the rock shaft 22 and journaled between the forward side frame members 1 and a bracket 29 secured to the rear side frame is a second rock shaft 30 having a lower elevator arm 31 secured thereto underneath the upper elevator arm 24. The forward end of the rock shaft 30 is provided with a crank arm 32 carrying the cam roller 33 and the cam roller is positioned in a cam groove 34 formed on the inside of a second cam wheel 35 carried on the forward end of the driven shaft 16. Thus as the upper rock shaft 22 and elevator arm are oscillated as previously described the lower rock shaft 30 and elevator arm 31 will simultaneously be oscillated by movement of the cam roller 33 in the cam groove 34.

The right or free ends of the elevator arms 24 and 31 are pivotally connected to an elevator bar 36 having an upwardly extending portion 37 to the upper end of which is attached a bracket 38 defining a transversely extending, upwardly opening T slot 39. The T slot is arranged to receive a mating T block 40 secured to the underside of the flanged elevator table 41.

As is most clearly illustrated in Fig. 2 the cam groove 27 in the rear cam wheel 28 is provided with a substantially constant radially advanced portion 42 throughout half of its circumference and connected at its ends to an irregular radially recessed portion 43. Thus as the cam wheel 28 and driven shaft 16 are rotated in the direction indicated by the arrow in Fig. 2, the cam roller 26 and crank arm 25 will maintain the upper rock snarl in the substantially constant position throughout half of the rotation of the driven shaft and will then rapidly advance the upper elevator arm 24 longitudinally in the direction of travel of the loading conveyor 19 and less rapidly return the upper arm to the retracted position shown by the full lines in Fig. 1.

Simultaneously with the motion of the upper elevator arm just described, the cam slot 34 in the forward cam wheel 35 will actuate the cam roller 33 from a substantially constant radially advanced portion at 44 through a rapidly retracting portion 45 and advancing portion 46. Motion of the cam roller through this cam groove will rapidly depress the lower elevator arm 31 while traversing the retracting portion 45 of the groove. The advancing portion 46 will raise the elevator bar 36 and the constant portion 44 will hold the elevator in raised position during the functioning of the transfer mechanism 6. The recessed portion 43 of the cam groove 27 is angularly disposed with respect to the retracting portion 45 of the cam groove 34 so as to retract the upper elevator arm during the time when the elevator and lower elevator arm are in lowered position. This retracts the elevator horizontally to register with the next succeeding pocket on the loading conveyor. Vertical motion of the elevator bar is thus supplied principally by the lower elevator arm and rock shaft while horizontal guiding motion to the upper end of the elevator bar and the elevator is supplied by the upper elevator arm 24. It will be appreciated that the cam contours illustrated have been designed to function in the particular wrapping machine shown having a particular spacing between the loading conveyor and the wrapping table and operating through elevator arms of the particular length shown. Obviously cam grooves of different contour could be devised to impart the desired motion to the elevator bar and elevator where a different vertical travel of the elevator was desired or where a different length of elevator arms was employed. The function of the cam grooves 27 and 34 is to direct the motion of the elevator 41 upwardly as shown by the arrows in Fig. 2 through an initial position of the loading pocket illustrated by dotted lines at 47 and to return the elevator to its lowered position in time to pass through a final position of the loading pocket illustrated at 48 as the loading conveyor is continuously advanced.

It should be understood that while I have described my elevator mechanism in connection with a cookie or food wrapping machine, I do not intend to so limit its use within the terms of my claims. The elevator mechanism is equally effective for the wrapping of various types of articles and eliminates the objectionable starting and stopping of the loading conveyor which causes vibration and mechanical trouble in the conveyor and its associated machinery. Another advantage of my elevator is that it eliminates sliding parts which may become sticky and jammed from particles falling from the objects being loaded. The elevator may further be

used to transfer articles to or from a continuously moving conveyor in any circumstance besides a wrapping operation where such a transfer is desirable.

I have thus illustrated and described a highly practical commercial embodiment of my elevator mechanism and have not attempted to illustrate other modified forms thereof as it is believed that such minor changes as are necessary to adapt the mechanism to specialized circumstances will readily be understood by persons skilled in the wrapping machine art.

Having thus described my invention, what I claim as new and desire to secure by Letters Patent, is:

1. In combination with a wrapping machine having a conveyor with work advancing flights thereon and wrapping mechanism positioned above said conveyor, said conveyor having its working reach disposed generally horizontally, said flights having openings in the bottoms thereof, elevator mechanism for lifting articles carried by successive flights of said conveyor to said wrapping mechanism comprising, a generally vertical elevator bar having an elevator plate thereon smaller than said openings and adapted to be passed through said flights, a lower elevator arm having one end pivotally connected to said bar, an upper elevator arm having one end pivotally connected to said bar at a point spaced from said first arm, a lower rock shaft secured to the other end of said lower arm, an upper rock shaft having a crank arm thereon, said crank arm being pivotally connected to the other end of said upper elevator arm, a cam shaft having a pair of rotary cams thereon, an actuating arm secured to said lower rock shaft and engageable with one of said cams to actuate said lower rock shaft to raise and lower said bar, another actuator arm secured to said upper rock shaft and engageable with the other of said cams to actuate said upper elevator arm to advance and retract said elevator bar means for continuously driving said conveyor, and means for driving said cam shaft in timed relation to the speed of the continuously driven conveyor.

2. In combination with a wrapping machine having a conveyor with work advancing flights and wrapping mechanism positioned above said conveyor, said conveyor having its working reach disposed generally horizontally, said flights having openings in the bottoms thereof, elevator mechanism for lifting successive articles from said conveyor flights to said wrapping mechanism comprising, a generally vertical elevator bar having an elevator plate thereon smaller than said openings and adapted to be passed through said flights, a first elevator arm having one end pivotally connected to said bar, a second elevator arm having one end pivotally connected to said bar at a point spaced from said first arm, a first rock shaft secured to the other end of said first arm, a second rock shaft having a crank arm thereon, said crank arm being pivotally connected to the other end of said second elevator arm, a cam shaft having a pair of rotary cams thereon, an actuating arm secured to said first rock shaft and engageable with one of said cams to actuate said first rock shaft to raise and lower said bar, another actuator arm secured to said second rock shaft and engageable with the other of said cams to actuate said second elevator arm to advance and retract said elevator bar means for continuously driving said conveyor, and means

for driving said cam shaft in timed relation to the speed of the continuously driven conveyor.

3. In combination with a wrapping machine having a conveyor and wrapping mechanism positioned thereabove, said conveyor having a series of open bottom article holding pockets positioned therealong, mechanism for transferring articles from said conveyor to said wrapping mechanism comprising, a driven shaft arranged to drive said conveyor continuously, a pair of cam wheels carried on the ends of said driven shaft and each defining a cam groove, said grooves being of different contour, an upper rock shaft having a crank arm thereon with a roller arranged to be actuated by one of said cam grooves, a second crank arm on said upper rock shaft positioned underneath said conveyor, an upper elevator arm pivotally connected to said second crank arm, a second rock shaft positioned below said first rock shaft, a third crank arm on said second rock shaft and having a cam roller arranged to be actuated by the other of said cam grooves, a lower elevator arm secured to said second rock shaft, an elevator bar pivotally connected to the ends of said elevator arms at points spaced along said bar, said bar extending upwardly above said upper elevator arm, and an elevator member carried on the upper end of said elevator bar, said cam grooves being arranged to actuate said elevator bar to move said elevator upwardly through a pocket of said conveyor to a delivery position at said wrapping mechanism and downwardly through said pocket to a lowered position of said elevator while said pocket is continuously advancing and retract said elevator to a starting position under a succeeding pocket on said conveyor.

4. In combination with a wrapping machine having a conveyor and wrapping mechanism positioned thereabove, said conveyor having a series of open bottom article holding pockets positioned therealong, mechanism for transferring articles from said conveyor to said wrapping mechanism comprising, a cam shaft, a pair of cam members carried on said driven shaft and each defining a cam groove, a first rock shaft having a crank arm thereon with a follower arranged in one of said cam grooves, a second crank arm on said first rock shaft positioned underneath said conveyor, a first elevator arm pivotally connected to said second crank arm, a second rock shaft, a third crank arm on said second rock shaft and having a cam follower arranged in the other of said cam grooves, a second elevator arm secured to said second rock shaft, an elevator bar pivotally connected to the ends of said elevator arms at points spaced along said bar, said bar extending upwardly above said elevator arms, and an elevator member carried on the upper end of said elevator bar, said cam grooves being arranged to actuate said elevator bar to lift said elevator upwardly through a pocket of said conveyor to said wrapping mechanism and downwardly through said pocket to a retracted position of said elevator while said pocket is continuously advancing, means for continuously driving said conveyor, and means for driving said cam shaft in timed relation to the speed of the continuously driven conveyor.

5. In combination with a wrapping machine having a loading conveyor and wrapping mechanism positioned thereabove, said conveyor having a series of open bottom article holding pockets positioned therealong, mechanism for transferring articles from said conveyor to said wrapping

mechanism comprising, upper and lower elevator arms, an elevator bar pivotally connected to said elevator arms, a rock shaft secured to one end of one of said arms for imparting oscillating rotary motion thereto, a second rock shaft having a crank thereon pivotally connected to the other of said arms for imparting oscillating motion thereto parallel to said conveyor, means for continuously driving said conveyor, and cam members driven in timed relationship to said loading conveyor for actuating said rock shafts to raise and lower said elevator bar through each pocket of said loading conveyor as said conveyor is advanced.

6. In a wrapping machine, the combination 15 with wrapping means, of a feed conveyor disposed in a plane below the wrapping means and having a plurality of uniformly spaced article holders having openings for the passage of an elevator therethrough, an elevator for transferring articles to be wrapped from said feed conveyor to said wrapping means, means for vertically reciprocating said elevator through said openings from a point below the feed conveyor to delivery position relative to said wrapping means, 20 means for continuously driving said conveyor, and means for simultaneously horizontally reciprocating said elevator in the vertical plane of the path of travel of said feed conveyor synchronized with

the travel thereof and with the vertical reciprocation of said elevator whereby the elevator successively passes through the article holders to transfer articles therefrom to said wrapping means.

5 JOHN W. SMITH.
